STARTER DRIVE CONTROL

William L. McGrath, Elmira, N. Y., assignor to
 Eclipse Machine Company, Elmira, N. Y., a corporation of New York

Application October 24, 1932, Serial No. 639,355

10 Claims. (Cl. 290—38)

This invention relates to a starter drive control for internal combustion engines and more particularly to an arrangement for automatically operating the starting mechanism of internal combustion engines under the control of the ignition switch key thereof.

It is an object of the present invention to provide a novel semi-automatic engine starter control arranged so that the operator starts the cranking action as an incident to placing the engine in operative condition, and the cranking is interrupted either by the self operation of the engine or, if the engine fails to start, by the operator incidental to his rendering the engine inoperative.

Another object is to provide such a device in which the starting mechanism is normally urged toward operative position but is arranged to be moved out of such position by the self operation of the engine and is held out by a latch controlled by the ignition switch key.

A further object is to provide such a device which is simple and economical in construction and efficient and reliable in operation.

Further objects and advantages will be apparent to those skilled in this art from the following description taken in connection with the accompanying drawings in which:

Fig. 1 is a semi-diagrammatic illustration of a preferred embodiment of the invention in normal or idle position, certain parts thereof being shown in section;

Fig. 2 is a similar view showing the parts in the positions assumed during the self-operation of the engine;

Fig. 3 is a view similar to Fig. 1 showing a slightly different embodiment of the invention, the parts being shown in their normal or idle positions;

Fig. 4 is a semi-diagrammatic view partly in section of another embodiment of the invention, the parts being shown in cranking position; and

Fig. 5 is a detail of the ignition switch illustrated in Fig. 4 in the engine-running position.

Referring to Fig. 1, there is illustrated a starting system for an internal combustion engine including a motor 1, a battery 2, grounded at 3, and connected by a lead 4 to a starting switch 5 which in turn is connected by a lead 6 to the starting motor, the motor being grounded to complete the starting circuit.

A cranking connection is provided between the motor and a member such as a flywheel gear 7 of the engine to be started, which is here illustrated in the form of a pinion 8 which is

loosely journaled on the extended shaft 9 of the motor 1 and is connected thereto through an overrunning clutch 11 which has a spline connection with said motor shaft 9 and is arranged to be moved longitudinally thereon by means of a shifting lever 12. This cranking connection may be of any suitable construction and is illustrated as the type shown and described in applicant's prior Patent 1,705,938 patented March 19, 1929. Since the particular form of cranking mechanism forms no part of the present invention, it is believed that a further description thereof is unnecessary, it being merely noted that the drive is of such type that an engaging member such as the pinion 8 is moved longitudinally into and out of mesh with the engine gear 7 by the rocking motion of the lever 12, and that the pinion 8 is permitted to overrun the motor shaft 9 when the engine starts.

According to the present invention, the lever 12 is suitably pivoted at 13 to an extension 14 of the frame of the motor, and is arranged to be actuated by means of a piston 15 having a piston rod 16 connected to the free end 17 of said lever 12 as by means of a link 18. The piston 15 is arranged to reciprocate within a fixedly mounted cylinder 19, suitable obturating means 20 being provided for preventing flow of gas around the piston 15, and suitable packing means 21 being provided in the inner head 22 of said cylinder for the piston rod 16. Means is provided for urging the starting mechanism toward operative position in the form of a spring 23 bearing against the piston 15 and the outer head 24 of the cylinder 19, whereby the pinion 8 is normally meshed with the engine gear 7. Means are further provided for rendering the starting mechanism inoperative responsive to self operation of the engine, such means being here shown to comprise conduits 25 and 26 arranged to connect the opposite ends of cylinder 19 to the engine exhaust and intake manifolds respectively of the engine whereby the pressure differential caused by the self operation of the engine causes the piston 15 to be moved to the left against the pressure of spring 23, thus disengaging the pinion 8 from the flywheel gear 7 as illustrated in Fig. 2.

According to the present invention, manually controllable means for retaining the starting mechanism in inoperative position is provided comprising a latching device and a manual switch 27 for controlling the starting operation, which switch is preferably as indicated the ignition

switch for the internal combustion engine. Switch 27 is arranged to control the position of the starting mechanism by means of an electric latch indicated generally by numeral 28, and is arranged to control the energization of the starting motor as by means of a solenoid 29 which operates the starting switch 5.

Referring first to the electric latch 28, one form of such device is here illustrated as comprising a plunger 31 having an armature 32 normally maintained in its lower position as illustrated in Fig. 1 by suitable means such as a spring 33 but arranged to be raised into locking position as shown in Fig. 2 by means of a solenoid 34 controlled through the lead 35 from the ignition switch 27 whereby closure of said switch renders said latch operative. Plunger 31 is provided with a latching shoulder 36 adapted to engage an abutment 37 on the piston rod 16 when the plunger 31 is in its upper position, such engagement being arranged to hold the piston 15 in its releasing position, thus maintaining the pinion 8 out of engagement with the gear 7 as shown in Fig. 2. Upon deenergization of solenoid 34 by the opening of ignition switch 27, the spring 33 is adapted to release the shoulder 36 from the abutment 37 and allow the return of the piston 15 to its normal position by means of the spring 23.

The control circuit for solenoid 29 comprises a lead 38 from the ignition switch 27, a switch 39 arranged to be closed by the lever 12 when in its normal or idle position, and a ground connection 41 to complete said circuit. The starting motor 1 may thus be energized by closure of the ignition switch 27 when the cranking connection is in operative condition. Suitable means such as a spring 42 is provided for opening the switch 39 when the lever 12 is moved to demesh the pinion 8 whereby the solenoid 29 is deenergized and the starting switch 5 is opened.

In the operation of this embodiment of the invention, starting with the parts in their normal or idle positions as illustrated in Fig. 1, closure of the ignition switch 27 causes closure of the starting switch 5 by reason of the energization of solenoid 29, whereby the starting motor 1 is energized to crank the engine. During this cranking operation, a certain amount of vacuum is created in the engine intake which will be transmitted through the conduit 26 to the cylinder 19, but it will be understood that this vacuum is entirely inadequate to overcome the spring 23 to move the piston to its disengaging position, and since there is substantially negligible pressure in the exhaust manifold during cranking, the piston 15 remains in its normal position and the cranking of the engine continues uninterruptedly.

Closure of the ignition switch 27 also energizes the solenoid 34 of latch 28 whereby plunger 31 is raised so that the locking shoulder 36 engages the piston rod 16 and lies in the path of the abutment 37.

When the engine becomes self-operative, the increase in vacuum in the intake manifold and the generation of pressure in the exhaust manifold combine to overcome the spring 23 and move the piston 15 to the left causing the pinion 8 to be withdrawn from mesh with the engine gear 7. At this time the movement of the piston rod 16 causes the abutment 37 to ride under the shoulder 36 of plunger 31 whereby the piston rod 16 is latched in its disengaging or engine-running position. The disengaging motion of the lever 12

releases the switch 39 causing the circuit of solenoid 29 to be broken, thus opening the starting switch 5 and causing the motor to be deenergized. As long as the ignition switch 27 remains closed, the parts of the starting mechanism are maintained in the position illustrated in Fig. 2 with the starting switch open and the cranking connection in disengaged position. When the ignition switch is opened to stop the engine, the latching solenoid 34 is deenergized, allowing the spring 33 to move the plunger 31 to its idle position, thus releasing the piston rod 16 which returns to its idle position when the intake vacuum and exhaust pressure have become dissipated due to the stopping of the engine. The pinion 8 is thus caused to remesh with the flywheel gear 7, and the switch 39 is reclosed so that the parts resume their normal or idle positions as illustrated in Fig. 1.

A second embodiment of the invention is illustrated in Fig. 3 in which provision is made for maintaining the cranking connection inoperative when the ignition switch is opened, by preventing the reengagement of the starting pinion with the engine gear, such reengagement being caused to take place upon subsequent reclosure of the ignition switch. For this purpose, the plunger 31 is provided with a second shoulder 43 adapted to engage a second abutment 44 on the piston rod 16, this abutment 44 being arranged slightly to the rear of the abutment 37 with respect to the meshing movement of the piston rod 16. The remaining elements of the structure are similar to those illustrated in Figs. 1 and 2 and are similarly numbered, the intake and exhaust manifolds 45 and 46 of the engine 47 being also illustrated.

The operation of this embodiment of the invention is the same as that previously described insofar as the starting operation is concerned. However, upon opening of the ignition switch 27 to stop the engine, the release of the plunger 31 causes the shoulder 43 to move into the path of the abutment 44 whereby the starting mechanism is maintained out of its operative position after the engine stops.

Upon reclosure of the ignition switch 27, the solenoid 34 raises the plunger 31, thus releasing the abutment 44, but since the abutment 37 has moved beyond the position where it could be engaged by the shoulder 36, the piston rod 16 is released and the starting mechanism moved by the spring 23 into operative position. Cranking and demeshing thereupon take place as hereinbefore described.

It will be noted that in the embodiments of the invention heretofore set forth, the current is permitted to flow continually through the latch solenoid 34 to maintain said latch operative as long as the ignition switch remains closed. It will be understood that the solenoid will preferably be so designed that this current flow will be insignificant and unobjectionable. However, there is illustrated in Fig. 4 an embodiment of the invention in which an electric latch is provided which is normally operative and calls for a merely momentary energization of the latch-controlling solenoid for releasing the latch.

In this embodiment of the invention the parts of the starting mechanism and of the controlling means are the same as described in connection with Figs. 1 and 2 except that the latching elements 36a and 37a are formed on the upper side of the piston rod 16, and the ignition switch 27a is provided with a separate contact point 48 con-

nected by a lead 49 to the solenoid 34 for controlling the same, a spring 51 being preferably provided for disconnecting the ignition switch arm from the contact 48 when the switch arm is released, as illustrated in Fig. 5.

In the operation of this embodiment of the invention, the starting operation is brought about by the operator moving the ignition switch 21a to close the ignition and starting relay circuits, and then moving said switch further against the spring 51 so as to close the latch solenoid circuit through the contact 48, as illustrated in Fig. 4. The plunger 31 is thereupon raised to release the starting mechanism whereupon engagement of the cranking mechanism and energization of the starting motor take place.

Release of the ignition switch 21a by the operator allows the spring 51 to return it to the engine-running position illustrated in Fig. 5. This causes the plunger 31 to be released and moved by the spring 33 to its lower position bringing the shoulder 36a into the path of the abutment 31a. The cranking of the engine continues, however since the circuit for the starting relay is not interrupted.

When the engine starts, the piston 15 is moved to the left into its disengaged position as above described, and is latched in that position by the elements 36a and 37a regardless of the subsequent stopping of the engine and/or the opening of the ignition switch. Restarting is obtainable at any time by the manipulation of the ignition switch to engage the contact 48 as above described.

It will be understood that in all the embodiments of the invention illustrated, if the engine fails to start, cranking may be interrupted by opening the ignition switch.

Although certain embodiments of the invention have been shown and described in detail, it will be understood that other embodiments are possible and that various changes may be made in the details and arrangements of the parts without departing from the spirit of the invention as defined in the appended claims, the parts illustrated being shown more or less diagrammatically in order to show the function thereof to the best advantage.

What is claimed is:—

1. In an engine starter control, starting gearing, yielding means constantly urging said gearing toward operative position, means responsive to self-operation of the engine for moving said gearing to inoperative position, means for positively retaining the starter gearing in inoperative position and manually controlled means for releasing said retaining means.

2. In an engine starter control, starting gearing, means urging said starting gearing toward operative position, means responsive to self-operation of the engine for moving said gearing to inoperative position, a latch for retaining the starting gearing in inoperative position, and manually operable means for releasing said latch.

3. In combination with an internal combustion engine having an ignition mechanism including a manually operable ignition switch, starting mechanism therefor including a motor and means for connecting the motor to crank the engine, means tending to make the connecting means operative, and means under the control of a latch controlled by said ignition switch for maintaining said connecting means inoperative.

4. In combination with an internal combustion engine, having an ignition mechanism including

a manually operable ignition switch, starting mechanism therefor including a motor and means for connecting the motor to crank the engine, means tending to put the connecting means into operative condition, means responsive to self-operation of the engine for moving said connecting means into inoperative position, and a latch controlled by said ignition switch for holding said connecting means in inoperative position.

5. An electrical starting system for internal combustion engines including a battery, a motor, means for connecting said motor with a member of an engine to be started, means for biasing the connecting means toward operative position, means for holding the connecting means in inoperative position, means for energizing the starting system when the connecting means is in operative position, and manually operable means for controlling the release of the holding means and the energization of the starting system. 20

6. In combination with an internal combustion engine, starting mechanism therefor including a starting motor and means for connecting the motor to crank the engine, yielding means constantly urging the connecting means into operative condition, means for energizing the starting motor when the connecting means is in operative condition, means responsive to self operation of the engine for rendering said connecting means inoperative, and manually controllable means for 30 positively maintaining the connecting means inoperative and for controlling the energization of the starting motor.

7. In combination with an internal combustion engine, an ignition system therefor including an ignition switch, starting mechanism therefor including a starting motor and means for connecting the motor to crank the engine, means for urging the connecting means into operative position, means for energizing the starting motor when the connecting means is in operative position, means responsive to self-operation of the engine for rendering said connecting means inoperative, means including a latch for holding the connecting means in inoperative position, and means rendering said latch operative upon closure of the ignition switch. 35

8. In combination with an internal combustion engine, an ignition system therefor including an ignition switch starting mechanism therefor including a starting motor and means for connecting the motor to crank the engine, means for urging the connecting means into operative position, means for energizing the starting motor when the connecting means is in operative position, means responsive to self-operation of the engine for rendering said connecting means inoperative, means including a latch for holding the connecting means in inoperative position, means rendering said latch operative upon closure of the ignition switch and means for releasing said latch when the ignition switch is opened. 50

9. In combination with an internal combustion engine, an ignition system therefor including an ignition switch, starting mechanism therefor including a starting motor and means for connecting the motor to crank the engine, means for urging the connecting means into operative position, means for energizing the starting motor when the connecting means is in operative position, means responsive to self-operation of the engine for rendering said connecting means inoperative, means including a latch for holding the connecting means in inoperative position, means rendering said latch operative upon closure of 75

the ignition switch, and means for maintaining the connecting means in inoperative position when the ignition switch is opened, but operative on reclosure of said switch to release the connecting means and allow it to move to operative position.

10. In combination with an internal combustion engine, an ignition system therefor including an ignition switch, starting mechanism therefor including a starting motor and means for connecting the motor to crank the engine, means for

urging the connecting means into operative position, means for energizing the starting motor when the connecting means is in operative position, means responsive to self-operation of the engine for rendering said connecting means inoperative, means including a normally operative latch for holding the connecting means in inoperative position, and means rendering said latch inoperative by closing movement of the ignition switch.
